UNITED STATES PATENT OFFICE.

JOSEPH A. McELROY, OF NEW YORK, N. Y.

SPRINKLER.

1,032,558.

Specification of Letters Patent. Patented July 16, 1912.

Application filed January 3, 1911. Serial No. 600,389.

To all whom it may concern:

Be it known that I, JOSEPH A. McELROY, a citizen of the United States of America, and a resident of New York, county and 5 State of New York, have invented certain new and useful Improvements in Sprinklers, of which the following is a specification, reference being had to the accompanying drawings, forming a part thereof.

10 My invention relates to sprinkler heads of the class employed in fire extinguisher systems and consists in a novel form and construction by which a valve is normally held tight against its seat but is displaced 15 under fire conditions, by the melting of a fusible connection.

The main objects of my invention are to improve and simplify structures of this character, and particularly to increase their 20 sensitiveness so that they will be promptly and surely operated under fire conditions.

To these ends my invention consists in certain novel details of construction and arrangement of parts, and in order that my 25 invention may be fully understood, I will now proceed to describe a structure constituting an embodiment thereof, reference being had to the accompanying drawings illustrating the same, and will then point 30 out the novel features in claims.

In the drawings: Figure 1 is a view in part side elevation and part central longitudinal section of a sprinkler head constructed in accordance with my invention. 35 Fig. 2 is a view in central longitudinal section therethrough upon a plane at right angles to the plane of section of Fig. 1. Fig. 3 is a detail perspective view of certain intermediate spacing elements employed, showing them as individually separated, as well as removed from the remaining structure.

The device in general comprises a tubular hub 5 externally screw-threaded so that it 45 may be readily connected to the end of a pipe, the upper portion 6 of the said hub constituting a valve seat, a yoke 7 in the form of arms which rise upward from the said hub, an adjustable abutment 8 supported by the said yoke at its upper end, a valve 9 fitted to the said valve seat 6, and intermediate spacing elements 10, 11 and 12, disposed between the abutment 8 and the valve 9. The elements 10 and 12 are angular in 55 form as is clearly shown in Figs. 2 and 3, the longer arms thereof being disposed ver-

tically, and the shorter arms horizontally and in respective engagement with the said abutment 8 and valve 9. The long arms of the elements 10 and 12 are arranged to be united by means of the element 11 which constitutes a connecting strip, the said element being soldered to the elements 10 and 11 as shown at 13 in Fig. 2, by a form of solder having the required low melting or fusing point. Intermediate its ends the element 11 is provided with a central stud 14 which constitutes an abutment against which the extremities of the longer arms 10 and 12 bear. These extremities are preferably pointed as appears in Fig. 2, whereby their point of engagement is limited, and for convenience in assembling the parts the stud 14 may be provided with a head 15. The elements 10 and 12 are conveniently provided each with a lateral abutment 20 disposed above and below the extremities of the element 11, preferably in close proximity, but out of direct contact, therewith, a portion of the fusible solder 13 bridging 25 the slight gap thus left. The abutment 8 is conveniently in the form of a threaded stud having a pointed end which bears against the short arm of the upper intermediate element 10 and the upper extremity of the stud is conveniently provided with a cap 30 which serves not only as a part by which the abutment 8 may be adjusted, but also as a deflecting device in the operation of the sprinkler. The upper side of the valve 9 is 35 provided with a central conical projection 17 in line with the pointed end of the abutment 8 and which bears against the short arm of the lower intermediate member 12. The longitudinal arms of the members 10 and 12 are arranged in a line to one side of the central line which passes through the pointed extremity of the abutment 8 and the conical projection 17 of the valve 9 as 40 clearly appears in Fig. 2.

When the parts are assembled as is shown in Figs. 1 and 2 of the drawings, the abutment 8 is so adjusted that the valve 9 is forced down upon the seat, it being understood that pressure is normally applied to 45 lift the valve either by compressed air in the pipe to which the hub 5 is connected in a dry pipe system, or by water under pressure in such pipe, in such systems wherein water is allowed normally to rest in the distributing 50 pipes. Under conditions of fire, the solder 13 will be melted and by reason of the fact

that there is but a single thickness of metal on either side of the solder, such solder will be quickly fused at such times. When the solder is so fused the fluid pressure beneath 5 the valve will immediately break joint between the elements 10 and 12, owing to the fact that the line of pressure throughout is out of line with the longitudinal portions thereof. The parts 10, 11 and 12 will be 10 thrown out of position laterally and apart, and the valve 9 will fly away from its seat, so as to form a clear passage for the water which at this time will be admitted through the hub 5. This water will strike the upper 15 deflecting element 16 and will be distributed in a fine spray throughout a considerable zone, as is common in this class of device.

It will be noted that while the lateral abutments 20 act to strengthen the device, 20 in that less dependence is placed upon the invisible solder union between the elements 10 and 12 and the element 11, and the engagement between the pointed ends of the elements 10 and 12, and the central abutment 25 14; they do not interfere in any way with the "breaking joint" when the solder fuses. This is due to the fact that in any event they act to withstand longitudinal strain only and in no way affect the lateral movement of 30 the parts such as takes place when joint is broken; and second, in the preferable arrangement of the parts as above described, these lateral abutments 20 do not actually engage the extremities of the element 11 so 35 that when the solder fuses there is no connection or engagement between them at all. The valve may be of any suitable form but preferably the face thereof is composed of two aluminum disks 18 with a disk 19 of 40 cork between them. The aluminum is substantially non-corrosive and hence obviates any tendency of the valve to stick to its seat, due to corrosion, while the cork forms a yielding cushion whose function is to absorb 45 vibration, and to permit the valve to be forced to its seat with a yielding pressure.

What I claim is:

1. A strut for sprinkler heads comprising a pair of flat members in alinement with 50 each other, short arms projecting at right angles from opposite ends of said members but in the same direction, said arms being adapted to receive the holding pressure for the sprinkler valve, and a flat connecting strip soldered to the side of said members opposite the arms, said strip having a stud 55

projecting centrally therefrom in the direction of said arms between the ends of said members which are away from said arms.

2. A strut for sprinkler heads comprising 60 a pair of flat members in alinement with each other, short arms projecting at right angles from opposite ends of said members but in the same direction, said arms being adapted to receive the holding pressure for 65 the sprinkler valve, and a flat connecting strip soldered to the side of said members opposite the arms, said strip having a stud projecting centrally therefrom in the direction of said arms between the ends of said 70 members which are away from said arms, said stud forming an abutment for the arms and being provided with a shoulder to normally prevent lateral movement of said 75 ends.

3. A strut for sprinkler heads comprising 80 a pair of flat members in alinement with each other, short arms projecting at right angles from opposite ends of said members but in the same direction, said arms being 85 adapted to receive the holding pressure for the sprinkler valve, and a flat connecting strip soldered to the side of said members opposite the arms, said strip having a stud projecting centrally therefrom in the direction of said arms between the ends of said members which are away from the said arms, said stud forming an abutment for the arms and being provided with a shoulder to normally prevent lateral movement of said 90 ends, said abutting ends being sharpened.

4. A strut for sprinkler heads comprising 95 a pair of flat members in alinement with each other, short arms projecting at right angles from opposite ends of said members but in the same direction, said arms being adapted to receive the holding pressure for 100 the sprinkler valve, and a flat connecting strip soldered to the side of said members opposite the arms, said strip having a stud projecting centrally therefrom in the direction of said arms between the ends of said members which are away from said arms, said members having transverse abutments 105 on their sides to which said strip is soldered, in proximity to the opposite extremities of the strip.

JOSEPH A. McELROY.
